AUTOMATIC RADIO FREQUENCY SELECTOR

Leonard S. Stenerson, Salem, Oreg.

Application April 3, 1934, Serial No. 718,797

4 Claims. (Cl. 250—20)

The primary object of my invention is to provide means whereby a day's program of desired radio broadcasts having been initially indicated, they will be automatically dialed in chronological order on a radio receiver.

A further object of my invention is to provide means whereby advance controlled timing of radio receiver operation may be effected.

With radio receivers as ordinarily constructed it is necessary to manipulate the controls thereof whenever and as a change of program is desired. With my improved device, however, and in the embodiment thereof herein disclosed, a selection of broadcasts for the ensuing twenty-four hour period may be programmed at one time to be automatically released as scheduled.

In this way a radio receiver may be set to any desired combination of periods of receiving and of silence. Should certain daily broadcasts be desired the settings for such may be left undisturbed, and so long as they are desired they will be received at the set time.

My device also furnishes means whereby a radio receiver may be automatically turned on at a predetermined time and be automatically turned off at a subsequent time, with, if desired, selected intermediate periods of silence.

In the particular embodiment herein disclosed, the cycle of operation is based on a twenty-four hour interval, but it is to be understood that such interval is not to be considered as confined to twenty-four hours but may be made shorter or longer according to the requirements of the individual design. I have elected, in this disclosure, to illustrate and describe a device where-with program changes may be effected at thirty minute intervals. This interval is of course to be considered elective and may be made to conform to the design requirements.

I attain these objects by mechanism illustrated in the accompanying drawings, in which—

Fig. 1 is a diagram disclosing the principle of operation of my device.

Fig. 2 is a diagram disclosing an alternative type of construction for the chronometrically actuated switch associated with my device.

Fig. 3 is an enlarged sectional view showing in detail the construction of the contact points on my power actuated station selector. This view is taken along the line 3—3 of Fig. 1, looking in the direction indicated.

Fig. 4 is a fragmentary elevation, partly in section, of a portion of my digitally manipulative selector switch disclosing the details of the slide.

Fig. 5 is a fragmentary end view, partly in section, of the slide shown in Fig. 4.

Fig. 6 is a front elevation of an alternative form of digitally manipulative station selector.

Fig. 7 is an end elevation of the mechanism shown in Fig. 6.

Fig. 8 is a cross section of the device disclosed in Fig. 6.

Like reference characters refer to like parts throughout the several views.

I provide a chronometrically actuated switch A comprising an electric contact bar 1 fixedly mounted upon a drive shaft 2 and rotating therewith. A suitable chronometrical driving mechanism, preferably a synchronous motor 3, is connected by appropriate gearing, as spur gears 4 and 4A, to the shaft 2, imparting thereto rotation at a constant rate. I do not wish to limit myself to the use of a synchronous motor for this purpose as any suitable chronometrical driving means may be employed. Conductors 5 and 6 are provided to transmit electric energy to the synchronous motor 3. In the present embodiment of my device the shaft 2, and consequently the contact bar 1, is rotated once diurnally. Should it be desired to shorten or lengthen the time cycle of operation, the rate of rotation of the shaft 2 may be altered to conform, one complete rotation being required for one cycle. A plurality of electric contact plates 7, 7a, 7b, 7c, etc. 30 is disposed upon a plane dielectric member 8 which is disposed normal to the shaft 2. These contact plates are evenly spaced and are equidistant from the axis of the shaft 2, and are adapted for successive contact with the contact bar 1. The contact bar 1 has a width at its extreme end sufficient to over span, slightly, the gap between adjacent contact plates. The number of contact plates is dependent upon the number of possible settings desired in one complete time cycle. In the present instance there are forty-eight contact plates, permitting a possible change of radio receiver setting every thirty minutes during the twenty-four hour cycle.

To facilitate observation and to permit ready visual checking of the operation of the chronometrical drive a pointer 9 may be affixed to the shaft 2 and rotated in close relation to a graduated plane member 10 bearing suitable time denoting indicia.

A wiping contact member 12 is suitably disposed to coact with the contact bar 1 and is connected, via a source of electric energy as a battery 14, to one coil lead of a circuit breaking relay 13, the other coil lead of which is grounded.

I further provide a digitally manipulative station selector means B whereby my device may be set to select desired programs upon their release during the ensuing time cycle. This means 5 comprises a pair of parallelly disposed supporting dielectric strips 15 and 16, mounted upon opposite ends of a substantially rectangular dielectric panel 17. A plurality of parallelly disposed and mutually electrically isolated conductor bars 18, 18a, 18b, 18c, etc. are mounted across the dielectric strips 15 and 16 and are electrically connected by suitable conductors to contact plates 7, 7a, 7b, 7c, etc. respectively. The number 10 of conductor bars is numerically equal to the number of contact plates, a conductor bar and its complementary contact plate being in each one of the timing circuits.

Each of the conductor bars 18, 18a, 18b, 18c, etc. is provided with a contact slide as 19, 19a, 20 19b, 19c, etc. These slides are each adapted for selective longitudinal displacement on the conductor bars. Each of these slides comprises a body portion 20 adapted to slide freely along the contact bar embraced by it. A handle portion 21 25 is provided to facilitate manipulation of the slide and a spring contact 22 is affixed to each of the slides. A plurality of parallelly disposed conductor strips 23, 23a, 23b, 23c, etc., are mounted upon the dielectric panel 17 immediately below 30 and at substantially right angles to the conductor bars 18, 18a, 18b, 18c, etc. These conductor strips are mutually insulated and the end one is grounded, as at 23x. These conductor strips are adapted for selective engagement by each, any 35 or all of the contact slides, being adapted for contact by the spring contact 22. The spacing of the conductor strips and the contour of the engaging end of the spring contact 22 are so related that contact of the spring contact 22 is limited to but one conductor strip at a time. A suitable cover plate 24 may be disposed over the slide and conductor bars. Slots 25 are provided through which the slide handles 21 may protrude. The cover plate 24 may be fastened in place by 40 any suitable means as by screws 26 entering into supporting strips 15 and 16.

I further provide a power actuated station selector C having a plane dielectric member 27 upon which is adjustably mounted a plurality of contact points 28, 28a, 28b, 28c, etc. Upon the 50 number of these contact points is dependent the number of positions to which the radio receiver condenser shaft may be automatically set and accordingly the number of stations to which the radio receiver may be automatically tuned. For each of the contact points 28, 28a, 28b, 28c, etc. there is a corresponding conductor strip 23, 23a, 23b, 23c, etc., and these complementary parts are 55 mutually connected by suitable conductors.

The contact points 28, 28a, 28b, 28c, etc. are mounted upon the dielectric member 27. A substantially semi-circular arcuate slot 29 is disposed in the member 27. Each of the contact points 28 has preferably a key or feather 30 engaging the slot 29 and adapted to maintain the contact point in a position radial to the center about which the arcuate slot is generated. A binding screw 31, coacting with nut 32, clamps the contact point in the desired position. An arcuate recess 33 60 may be provided to engage opposite sides of the nut 32 to prevent rotation thereof, thus facilitating the adjustment of the contact point.

A shaft 34, disposed perpendicularly to the plane of the dielectric member 27, is journaled 70 at its one end in a suitable bearing mounted

therein and is supported at its other end by suitable attachment means, not here shown, to the condenser rotor shaft of the radio receiver with which my device is associated. The axis of the shaft 34 is preferably made to coincide with the 5 center about which the arcuate slot 29 is generated.

A contact arm 35 is affixed to the shaft 34 and is provided with a resilient contact tip 36 which is adapted to contact successively the contact 10 points 28, 28a, 28b, 28c, etc. The contact arm 35 is made of suitable conductor material, and is provided with a hub 37 which acts as an electric contact plate and coacts with a spring contact member 38 which is thus in circuit with that 15 one of the contact points contacted by the arm 35.

The spring contact member 38 is connected to one coil lead of a circuit making relay 40, the other lead of which is grounded.

Each of the contact points 28, 28a, 28b, 28c, etc. 20 represents a single position of the shaft 34 and of the radio receiver tuning condenser shaft, and therefore corresponds to a specific wave length, or frequency, and broadcasting station. Sharp tuning of the radio receiver may be effected by 25 adjusting the contact points to give the most effective condenser positions.

Gear 41 is fixedly mounted upon and adapted to rotate the shaft 34 by means of a gear 42 mounted upon the armature of a motor 43. The 30 motor 43 is energized by a suitable electric current as from a battery 44. The electric circuit between the motor 43 and the battery 44 is controlled by the circuit breaking relay 13, installed 35 in the motor-battery circuit.

A pair of electric conductors, 45 and 46 is disposed in the radio receiver power circuit, and this circuit is controlled by the circuit-making relay 40. In installations where it might be desired to control the radio receiver filament circuit rather than the power circuit, the conductors 45 and 46 may be incorporated in the filament circuit.

In operation, the handles 21 of the contact slides 19, 19a, 19b, 19c, etc.; on the digitally 45 manipulative station selector B are so manipulated as to bring the slide on the conductor bar, corresponding to each broadcast interval for the ensuing cycle, over and in contact with that conductor strip representing the desired radio broadcasting station. Referring to Fig. 1, contact plate 7, corresponding to the 30 minute period starting at 12 P. M. as indicated by the pointer 9, is in circuit with conductor bar 18, the slide 19 of which is in contact with conductor strip 23 which 50 in turn is in circuit with contact point 28. For those periods during which no broadcast is desired, the slides are placed to contact grounded conductor strip 23x. Slides 19e and 19g are shown so placed. The mechanism illustrated 55 discloses that the receiver is operating on the frequency corresponding to the condenser rotor position relating to the position of contact point 28 and coacting contact arm 35. In the position shown the electric circuit actuating the circuit 60 breaking relay 13 is closed, thus maintaining an open circuit to the motor 43 and causing arm 35 to be in stationary contact with the contact point 28, and causing the circuit making relay 40 to be energized, thus closing the power or filament 65 circuit of the radio receiver.

Upon the advancement of the contact bar 1 from contact plate 7 to contact plate 7a, the circuit through the circuit breaking relay 13 is opened, and the circuit through the motor 43 70

is closed, resulting in rotation of the shaft 34, through gears 41 and 42 and consequently of the arm 35 and the radio receiver condenser rotor. This rotation ordinarily continues until the contact tip 36 contacts that one of the contact points in the new circuit established by the advance of the contact bar 1. In Fig. 1 this would be contact point 28a, in series with contact plate 7a via conductor strip 23a, a slide 19a, and conductor bar 18a. When contact tip 36 contacts the contact point 28a, the circuit through circuit breaking relay 13 is closed and the circuit through the motor 43 is opened, stopping motor 33 and arresting contact tip 36.

15 During those periods through which no reception is desired, the respective contact-plate-to-conductor-bar circuits are grounded through their slides via conductor strip 23x. In Fig. 1, slides 19e and 19g are so placed, thus grounding 20 the circuits from contact plates 7e and 7g respectively, and also shunting out the motor actuated selector switch C and circuit making relay 40.

In all intervals during which relay 13 is de-energized, relay 40 is also deenergized. Relay 40 25 is also deenergized during all periods through which the grounded conductor strip is being utilized. The deenergization of relay 40 results in silencing the radio receiver by breaking the power or filament circuit in the receiver. This 30 construction results in a silent receiver during those periods through which reception is not desired and also during the periods in which station changes are being effected.

Should it be desired to maintain a station 35 setting over an interval of two or more periods of thirty minutes each, no interference with the broadcast will be had due to the fact that the width of the contact end of contact bar 1 is sufficient to over-span the space between adjacent contact plates, thus maintaining an unbroken circuit through the coil of the circuit breaking relay 13.

In Fig. 2 I disclose the details of an alternative type of chronometrically actuated switch. This 45 switch is characterized by the fact that the contact bar 1 instead of being advanced with constant angular velocity is advanced by even increments, the close spacing between stops, where necessitated by frequent program changes, making 50 this sometimes desirable. In this construction the shaft 2 has fixedly mounted thereupon a ratchet wheel 47. A pawl 48 pivotally mounted upon pin 49 is adapted to engage with the teeth of the ratchet wheel 47. An arm 50 is pivotally 55 mounted upon the shaft 2 and supports the pin 49. An armature 51 made of a material susceptible of magnetic attraction is mounted upon the arm 50. A stop 52 is arranged to limit the travel of the arm 50 to within predetermined 60 limits. A reactance element as a spring 53 is disposed relative to the arm 50 to maintain it at rest in a fixed position. An electric magnet 54 is arranged within range of the armature 51. The 65 electric magnet 54 is periodically energized from a suitable source of electric current as a battery 55, by means of contact arm 56 and contact point 57 which together provide means whereby the electric circuit of the battery 55 may be interrupted. The contact arm 56 and the contact 70 point 57 are suitably mounted as upon a support 59. A reactance element, as a spring 58, tends to separate the contact arm 56 and the contact point 57. A cam 60 driven through suitable gearing by a synchronous motor 61 which 75 is mounted to the support 59, provides means

whereby the contact arm 56 is periodically brought into contact with the contact point 57 thereby closing the circuit through the battery 55 and energizing the electric magnet 54. Suitable electric current may be supplied to the synchronous motor through conductors 5 and 6.

In Fig. 6 I disclose an alternative type of digitally manipulative station selector. In this type of station selector I provide a dielectric body member 62 which is provided with a concave surface 63. This concave surface is generated from a line lying upon one of the surfaces of the body member. A plurality of conductor strips 64 are partially embedded within the dielectric body member 62 being thereby mutually insulated. A shaft 65 is disposed through shaft supports 66. The axis of the shaft 65 coincides with the line about which the concave surface 63 is generated. The shaft supports 66 are secured to the body member 62 by suitable means as by screws 66a. A plurality of selector arms 67, formed preferably of suitable dielectric material, are disposed upon the shaft 65. These selector arms are each provided with a spacing hub 68. A spring contact 69 made from suitable conductor material is attached to each of the arms 67 by means of ratchet 71. The spring contacts 69 are each provided with terminals 72 to which are affixed flexible conductors 73 which emerge from the station selector through independent apertures as shown at 74. Each of the selector arms is provided with a projection 70 suitably arranged to be engaged by the fingers of the operator of the device.

Semi-cylindrical cover plate 75, provided with flanges 76, is disposed upon the body member 62 with its line of generation coinciding with that of the concave surface of the body member 62 and is fastened thereto by any suitable means as by screws 77. A plurality of slots 78 are disposed circumferentially about the surface of the cover plate. These slots are adapted to embrace the projections 70 of the selector arms. Indicia are disposed upon one of the radial flanges 76 and in alignment with the selector arms indicating the hour or fraction of an hour following which the indicated selector arm controls the position of the power actuated station selector. Suitable indicia 80 are disposed radially upon the semi-cylindrical cover plate. These last named indicia indicate the position to be assumed by the selector arms to cause the power actuated station selector to tune the radio receiver to the indicated station or wave length.

While the form of mechanism herein shown described is admirably adapted to fulfill the objects primarily stated, it is to be understood that it is not intended to confine the invention to the embodiment herein shown and described, as it is susceptible of embodiment in various forms, all coming within the scope of the claims which follow.

What I claim is:

1. In a device of the class described, the combination with a radio receiver tuning mechanism, of a plurality of electric timing circuits; a chronometrically actuated switch successively and individually actuating the electric timing circuits, the switch comprising a radial arm contacting, not over two at a time, a plurality of mutually isolated contact plates circumferentially disposed about the axis of the arm and simultaneously and continuously contacting a contact ring circumferentially disposed about the axis of the arm, and progressed by chronometrically controlled

- means coacting with the radial arm; a circuit breaking relay common to all of the electric timing circuits; a digitally manipulative selector switch having a plurality of conductor bars, conductor strips and contact slides, the conductor bars being individually connected to their complementary contact plates, one of the conductor strips being grounded, and all of the conductor strips being adapted for individual engagement with the conductor bars by means of the contact slides; and a power actuated station selector switch comprising a plurality of contact points mutually isolated and individually connected to their complementary conductor strips, a contact arm adapted to individually contact the contact points, contact means constantly contacting the contact arm, means for angularly displacing the contact arm, means for coordinating the displacement of the contact arm with the radio tuning mechanism, and means for rendering the radio receiver selectively inoperative.
2. In a device of the class described, the combination with a radio receiver tuning mechanism, of a plurality of electric timing circuits; a chronometrically actuated switch successively and individually actuating the electric timing circuits, the switch comprising a radial arm contacting, not over two at a time, a plurality of mutually isolated contact plates circumferentially disposed about the axis of the arm and simultaneously and continuously contacting a contact ring circumferentially disposed about the axis of the arm, and progressed by chronometrically controlled means coacting with the radial arm; a circuit breaking relay common to all of the electric timing circuits; a digitally manipulative selector switch having a plurality of conductor bars, conductor strips and contact slides, the conductor bars being individually connected to their complementary contact plates, one of the conductor strips being grounded, and all of the conductor strips being adapted for individual engagement with the conductor bars by means of the contact slides; and a power actuated station selector switch comprising a plurality of contact points mutually isolated and individually connected to their complementary conductor strips, a contact arm adapted to individually contact the contact points, contact means constantly contacting the contact arm, means for angularly displacing the contact arm, and means for coordinating the displacement of the contact arm with the radio tuning mechanism.
3. In a device of the class described, the com-

bination with a radio receiving tuning mechanism, of a plurality of electric timing circuits, a chronometrically actuated switch successively and individually actuating the electric timing circuits, the switch comprising a radial arm contacting, not over two at a time, a plurality of mutually isolated contact plates circumferentially disposed about the axis of the arm and simultaneously and continuously contacting a contact ring circumferentially disposed about the axis of the arm, and progressed by chronometrically controlled means coacting with the radial arm; a circuit breaking relay common to all of the electric timing circuits, a digitally manipulative selector switch comprising a dielectric body member having a concave surface, a plurality of conductor strips disposed longitudinally of the concave surface, a shaft, shaft supports positioning the shaft, a plurality of selector arms rotatably mounted upon the shaft, hubs integral with the selector arms and spacing them, terminals disposed upon an end of the selector arms, conductors affixed to the terminals, and a semi-cylindrical and slotted cover plate disposed upon the body member.

4. In a device of the class described, the combination with a radio receiving tuning mechanism; of a plurality of electric timing circuits, a chronometrically actuated switch successively and individually actuating the electric timing circuits the switch comprising a radial arm contacting, not over two at a time, a plurality of mutually isolated contact plates circumferentially disposed about the axis of the arm and simultaneously and continuously contacting a contact ring circumferentially disposed about the axis of the arm, and progressed by chronometrically controlled means coacting with the radial arm; a circuit breaking relay common to all of the electric timing circuits, a digitally manipulative selector switch comprising a dielectric body member having a concave surface, a plurality of conductor strips disposed longitudinally of the concave surface, a shaft, shaft supports positioning the shaft, a plurality of selector arms rotatably mounted upon the shaft, hubs integral with the selector arms and spacing them, terminals disposed upon an end of the selector arms, conductors affixed to the terminals, a semi-cylindrical and slotted cover plate disposed upon the body member, hour denoting indicia disposed longitudinally of the cover plate, and other indicia disposed circumferentially of the cover plate.

LEONARD S. STENERSON.
